United States Patent Office

Des. 186,523
Patented Nov. 3, 1959

186,523

CLIMBER SLIDE

George Hjelte, Los Angeles, Calif.

Application October 20, 1958, Serial No. 53,041

Term of patent 14 years

(Cl. D34—5)

Fig. 1

Fig. 2

Figure 1 is a perspective view of a climber slide showing my new design;

Figure 2 is a plan view taken along a line normal to the surface of the slide;

Figure 3 is an end elevational view, taken at the right-hand end of Figure 1; and

Figure 4 is a front elevational view of the slide.

I claim:

The ornamental design for a climber slide, substantially as shown.
